UNITED STATES PATENT OFFICE.

AUSTIN LEE CLAFLIN, OF LONDON, ENGLAND.

TYPE-WRITER COVER.

1,235,554.

Specification of Letters Patent.

Patented Aug. 7, 1917.

Application filed August 18, 1916. Serial No. 115,687.

To all whom it may concern:

Be it known that I, AUSTIN LEE CLAFLIN, a citizen of the United States of America, and resident of 30 Corringham road, Golders Green, London, England, have invented an Improved Type-Writer Cover, of which the following is a specification.

This invention relates to a typewriter cover of the kind adapted to inclose the machine with the exception of the keyboard and lined with sound-insulating material in order to deaden the noise occasioned by the operation of the machine, and has for its object to provide an improved cover which will enable access to the machine to be obtained with great facility.

A cover constructed in accordance with the present invention is provided with a counterweighted pivotally-mounted arcuate panel adapted to close the opening through which access is obtained to the typewriter.

Referring to the accompanying drawings, Figure 1 is a front elevation of one form of cover constructed according to this invention. Figs. 2 and 3 are cross sections thereof on the lines 2—2 and 3—3 respectively, Fig. 1.

The form of cover illustrated is designed for use on a drop-action typewriter table of well-known construction of which only the movable typewriter supporting surface *a* is shown with a typewriter *b* thereon.

The cover consists of a back *c* and end walls *d*, *d* which are secured to the supporting surface *a*, lateral sections or doors *e*, *e* hinged to the end walls *d*, *d*, a plate *f* slidably carried between the doors *e*, *e* opposite the keyboard of the typewriter, and an arcuate panel *g*. The back *c* is curved over at its upper margin so as to form with the panel *g* an arcuate top to the cover, and the end walls *d*, *d* are grooved as at *h* to guide the panel *g* which is carried by quadrant-shaped plates *j*, *j* revoluble about stub shafts *k*, *k* mounted between the end walls *d*, *d* and false walls *l*, *l*. On arms *m*, *m* constituting extensions of the plates *j*, *j* are adjustably mounted counterweights *n*, *n* adapted to balance the weight of the panel *g*, so that the latter may be slidden back in the grooves *h* with the minimum effort, and buffer springs or the like *o*, *o*, are arranged at the ends of the grooves to arrest the movement of said panel. The panel itself is composed for the greater part of its length (*i. e.* between the false walls *l*, *l*) of glass or like

transparent material in order that the typewriter and the matter written thereby may be viewed, the end portions of said panel being of wood and furnished with handles *p*, *p*, whereby the panel may be slidden back. To each of the end walls *d* and at the front edge thereof is hinged a door *e* extending inwardly from the end wall *d* almost to the frame of the typewriter *b* and adapted to be secured in closed position by a bolt *g* or like device engaging the supporting surface *a*. The inner edges of the doors *e*, *e* are grooved in order that a plate *f* of glass or metal may be slid therein. As shown in Fig. 2, this plate *f* lies in front of the main body of the typewriter but behind and above the keyboard so that the whole of the machine except the keyboard is inclosed by the cover. The plate *f* is preferably offset as at *r* to facilitate operation of the adjustable marginal stops (not shown) of the typewriter, and the doors *e*, *e* are provided with flanges such as *s* adapted to close the gaps occasioned by the offset portion *r*. The top of said portion *r* and also the top of one of the doors *s* is cut away as at *t* to accommodate the line-spacing lever *u* of the machine, which is made sufficiently long to project outside the cover. As shown, the supporting surface *a*, the back *c*, the false walls *l*, *l*, and the doors *e*, *e* are lined with felt or like sound-insulating material *v*.

The construction of the cover is such that while the typewriter may be operated in the usual manner as regards the keyboard and the line-spacing lever *u*, the effort necessary to slide back the panel *g*, when it is desired to make an erasure, insert fresh paper, or satisfy other requirement, is negligible owing to the pivotal mounting and the provision of counterweights; consequently, although the advantages of a sound-proof cover are obtained, the operation of the machine is practically the same as if no cover were placed thereover.

What I claim is:—

1. A typewriter cover comprising a body portion constituting the back and end walls and part of the top of the cover, lateral sections secured to said end walls and constituting together with a removable plate arranged between said sections the front wall of the cover, and a counterweighted, pivotally-mounted arcuate panel constituting the remainder of the top.

2. A typewriter cover comprising a body

- portion constituting the back and end walls and part of the top of the cover, lateral sections secured to said end walls and constituting together with a removable plate arranged between said sections the front wall of the cover, a counterweighted pivotally-mounted arcuate panel constituting the remainder of the top, said panel being formed in part of transparent material, and a lining of sound-insulating material on said back, end walls and lateral sections. 5 remainder of the top, said removable plate being slidable in grooves in said lateral section and being offset at its upper part, substantially as set forth. 45
3. A typewriter cover comprising a body portion constituting the back and end walls and part of the top of the cover, lateral sections secured to said end walls and constituting together with a removable plate arranged between said sections, the front wall of the cover, and a counterweighted, pivotally-mounted arcuate panel constituting the remainder of the top, a portion of the upper edge of said removable plate and of one of said lateral sections being cut away, substantially as set forth. 10 50
4. A typewriter cover comprising a body portion constituting the back and end walls and part of the top of the cover, lateral sections secured to said end walls and constituting together with a removable plate arranged between said sections the front wall of the cover, and a counterweighted, pivotally-mounted arcuate panel constituting the remainder of the top, said arcuate panel being carried by quadrant-shaped plates revolvable about stub shafts mounted on said end walls, substantially as set forth. 15 55
5. A typewriter cover comprising a body portion constituting the back and end walls and part of the top of the cover, lateral sections secured to said end walls and constituting together with a removable plate arranged between said sections the front wall of the cover, and a counterweighted, pivotally-mounted arcuate panel constituting the remainder of the top, said panel being formed in part of transparent material, a lining of sound-insulating material on said back, end walls, and lateral sections, a portion of the upper edge of said removable plate and of one of said lateral sections being cut away, said arcuate panel being carried by quadrant-shaped plates revolvable about stub shafts mounted on said end walls, and said removable plate being slidable in grooves in said lateral sections and being offset at its upper part, substantially as set forth. 20 60 65 70 75 80

AUSTIN LEE CLAFLIN.
